VENTILATOR

Clarence L. Metzgar, Media, and Francis M.
Lambert, Narberth, Pa.Application April 26, 1937, Serial No. 139,034
Renewed July 3, 1939

8 Claims. (Cl. 98—99)

The object of the invention is to provide improvements in ventilators broadly, but more especially in ventilators which are intended for use in such places as the windows of homes and offices, in which a minimum obstruction of light is desired, as well as a maximum passage of air without draft.

Another object therefore is to provide a ventilator, which is primarily composed of sections of transparent material, alternately positioned in spaced preferably parallel planes, and the neighboring edge portions of each pair of adjacent sections in the two planes, being connected with apertured spacing means or hollow partitions, and the whole being secured together by means of a suitable frame, which may but need not necessarily have one or more yieldingly positioned end sections, for securing the ventilator in operative position in a window or the like.

20 A further object, relating more to the details of its construction, resides in the fact that the apertures in the spaced walls of each of the hollow partitions are staggered, so as to break up or partially baffle the otherwise relatively direct flow of air through each partition, thereby preventing the passage of water through the ventilator, either as the result of a driving rain or the impingement of a hose stream against the same, and in addition there being also preferably 25 positioned in each such partition a strip of gauze, for the purpose of preventing the passage of insects, and minimizing also the passage of foreign particles in general, through the ventilator as a unit.

30 With these and other objects in mind, the invention comprises further details of construction and operation, such as are hereinafter described in the following description, when read in conjunction with the accompanying drawing, in which Fig. 1 is a front elevation of a ventilator comprising one embodiment of the invention; Fig. 2 is a horizontal section on the line 2—2 of Fig. 1; Fig. 3 is a vertical fragmentary section on the line 3—3 of Fig. 2; Fig. 4 is a vertical section on the line 4—4 of Fig. 3; and Fig. 5 is an enlarged fragmentary section through an end portion of a modified form of one of the said partitions.

35 Referring to the drawing, there is shown a plurality of transparent sections 1 and 2 of any suitable material, such as glass, "Cellophane", or similar cellulose derivative. These sections are alternately positioned in preferably spaced parallel planes, and it is to be understood that 40 the term "transparent" is intended to apply to

and anticipate all substances which pass light rays to a greater or less degree, whether entirely or partially transparent, or merely translucent, as compared with metallic and other substances which are completely opaque to light rays.

Throughout the body of the improved ventilator, the neighboring edge portions of the sections of each adjacent pair over-lap slightly, said end edge portions being bound, or otherwise secured, between the over-lapping flanges 3 of opposed channel members, the central portions 4 of which members are spaced apart to provide in each instance a hollow, transversely extending partition, and each of said central portions being provided with series of vertically spaced apertures 5, which 45 series are staggered with respect to each other in the opposed channel members. At their normal upper and lower limits, said members are separated by spacing means 6, through which, and also through the adjacent end portions of 50 said members, rivets, or other form of securing means 7 extend, as shown in Fig. 3. Preferably within each of said hollow partitions is positioned a section of wire mesh or gauze 9 for the purpose of sifting air passing between the opposed series 55 of partition apertures.

A modified form of this construction is shown in Fig. 5, in which the spacing means 6 are eliminated, and instead each of the central portions 4 of said channel members is provided with an 60 inwardly directed boss 8, between which is preferably positioned the adjacent end portion of a strip of suitable wire mesh or gauze 9, said members and said gauze being secured together by rivets, or equivalent means 10, passing through 65 said bosses and said gauze.

The upper and lower portions of the structure, thus described, are protected and partially surrounded by longitudinally extending channel members 11, while said last-named channel members are fixedly positioned with respect to said transparent sections and intervening partitions, by brackets 12, which are secured at 13 to the channel members 11 and provided with parallel end portions 14, which in Fig. 3 are shown as 70 also being secured between adjacent end portions of said first-mentioned channel members 4, in addition to the spacing means 6, while in Fig. 5 an end portion 14, of one of said braces, is shown as being secured together with said gauze between 75 the bosses 8.

The ventilator structure thus described may be considered as complete in itself, or may be provided, at either or both of its opposite ends, with means for yieldingly securing it operatively with 80 85

respect to a window, or the like, in which case one or more auxiliary end members 15, also of channel shape, are provided, the opposite parallel sides 16 of which end members slide with respect to the adjacent portions of the ventilator, while said end members are normally maintained in outermost spaced relation with the ventilator proper, by means of suitably positioned leaf springs 17, or the like, the construction and operation of said end members and positioning springs not comprising a part of the present invention.

From the structure here illustrated, it will be apparent that depending upon the horizontal extent of the several transparent sections 1 and 2, the ventilator as a whole offers but a minimum obstruction to the otherwise relatively free passage of light rays, and in fact, when transparent sections are employed, the diminution or obstruction offered to the passage of light rays is only caused by and to the relatively slight degree represented by the aggregate widths of the several hollow partitions described. Also, it will be quite obvious that, by staggering the apertures in the opposed walls of said hollow partitions, a driving rain or hose stream will be prevented from passing through said ventilator structure. On the other hand, air is relatively free to pass through such structure except that the force of a normal breeze will be broken to such an extent as to prevent a draft being detected upon the inner side of said ventilator when operatively positioned in a window, or the like. Also, the gauze section 9, it will be noted, effectively prevents the passage of insects, as well as minimizing the passage of foreign particles in general, past the improved ventilator as a unit.

Having thus described our invention, what we claim as new and desire to protect by Letters Patent of the United States is:

40 1. A ventilator, comprising a plurality of transparent sections in spaced planes, and apertured partition members extending transversely between said planes and connecting neighboring edge portions of adjacent sections.

45 2. A ventilator, comprising a plurality of transparent sections in spaced planes, and hollow partition members extending transversely between and connecting the neighboring edge portions of adjacent sections, the transversely extending walls of said partitions being provided with unaligned apertures.

50 3. A ventilator, comprising a plurality of transparent sections in spaced planes, hollow partition members extending between and supporting the neighboring edge portions of adjacent sections, the transversely extending walls of said partitions being provided with unaligned apertures, and gauze sections positioned within said partition members between said apertured walls.

55 4. A ventilator, comprising a plurality of sections positioned in substantially parallel planes,

hollow partition members extending transversely of and connecting neighboring edge portions of adjacent sections, the walls of said members being apertured, and gauze sections positioned within said members between said wall apertures. 6

5. A ventilator, comprising a plurality of sections in staggered relation in parallel planes, and a partition connecting neighboring edge portions of said sections, said partition being formed of two oppositely directed channel members comprising telescoping laterally positioned flanges, the central portions of which members are apertured and each pair of the adjacent flanges of which secure between them an edge portion of one of said sections. 10

6. A ventilator, comprising a plurality of sections in staggered relation in parallel planes, a partition connecting neighboring edge portions of said sections, said partition being formed of two oppositely directed channel members comprising telescoping laterally positioned flanges, the central portions of which members are apertured and each pair of the adjacent flanges of which secure between them an edge portion of one of said sections, the channel members of each pair being provided with inwardly directed bosses, and means to secure the members of each such pair together passing through said bosses. 15

7. A ventilator, comprising a plurality of sections in staggered relation in parallel planes, a partition connecting neighboring edge portions of said sections, said partitions being formed of two oppositely directed channel members comprising telescoping laterally positioned flanges, the central portions of which members are apertured and each pair of the adjacent flanges of which secure between them an edge portion of one of said sections, the channel members of each pair being provided with inwardly directed bosses to space said members apart, a section of gauze positioned between each pair of opposed bosses, and means to secure pairs of said members together with said gauze section positioned between them. 20

8. A ventilator, comprising a plurality of sections in staggered relation in parallel planes, a partition connecting neighboring edge portions of said sections, said partitions being formed of two oppositely directed channel members comprising telescoping laterally positioned flanges, the central portions of which members are apertured and each pair of the adjacent flanges of which secure between them an edge portion of one of said sections, the apertures in said channel members being staggered, a section of gauze between the members of each such pair, means to operatively space said members apart, and means passing through said spacing means to secure said members in operative relation. 25
